EUGÈNE FRANÇOIS CÔTE AND PAUL RAMBERT PIERRON, OF LYON, FRANCE.

ELECTRIC FURNACE FOR THE CONTINUOUS EXTRACTION OF ZINC FROM ITS ORES.

944,774.

Specification of Letters Patent. Patented Dec. 28, 1909.

Application filed May 14, 1907. Serial No. 373,627.

To all whom it may concern:

Be it known that we, EUGÈNE FRANÇOIS CÔTE, of 24 Rue Sully, electrical engineer, and PAUL RAMBERT PIERRON, of 1 Rue d' Algérie, electrical engineer, both of Lyon, Rhône, Republic of France, have invented an Electric Furnace for the Continuous Extraction of Zinc from its Ores, of which the following is a full, clear, and exact description.

Our invention is an improvement in electric furnaces, and consists in certain novel constructions and combinations of parts hereinafter described and claimed.

15 The object of the invention is to permit zinc ores, preferably poor blends, to be treated in a continuous manner for extracting the metal therefrom, and permitting the heating of crude blends without it being necessary to previously roast them in order to transform the sulfid into oxid.

20 Referring to the drawings forming a part hereof, the figure shows a vertical section of the furnace.

25 In the present embodiment of the invention, the reaction chamber *a* is provided with movable electrodes *b*, *b'*, and with a feed inlet *i* between the electrodes. The tap hole *t* is closed by the usual plug *u*, and at the opposite end of the chamber from the tap hole is an outlet *t'*.

The electrodes *b*, *b'*, are movable vertically as before stated, with respect to the chamber, and the furnace may be operated 35 either in resistance by causing the two electrodes to plunge in the bath in fusion, in the chamber, or with a single arc by plunging one electrode into the bath, and moving the lower part of the other to arcing distances with the matter in fusion. Either 40 method may be used according to the nature of the ore which is being treated and the kind of reaction desired to be effected with in the furnace. Should the sides of the furnace become foul during the working of the furnace in resistance, working with the arc for a few moments will automatically cleanse 45 them without opening the furnace.

The electrodes *b*, *b'* are connected at their 50 upper ends with screws *c*, *c'*, which traverse threaded nuts journaled in bearings *d*, *d'* in a supporting frame above the furnace, and the upper ends of the nuts are provided with bevel gears meshing with bevel gears 55 *e*, *e'*, by means of which the screws may be rotated to raise or lower the electrodes.

The feed inlet *i* is provided with a steel drill *n*, and to prevent choking of the inlet, the drill is mounted for rising and falling movement in the inlet. For imparting such movement to the drill, a screw-threaded rod *o* is connected with the upper end thereof, the said rod passing through a nut having rigid therewith a bevel gear meshing with the bevel gear *p* supported above the furnace.

The charging of the furnace is effected by suitable mechanism, not shown, which is operated by an electric motor *m*.

A hopper *l* is arranged above the furnace, and delivers to the inlet through a chute *k*. The tap hole *t* is as before stated, closed by a plug *u*, which is an electrode, and is provided with trunnions *z* which are journaled in the lower end of a lever *w* pivoted as at *x*, whereby the electrode may be swung into and out of the tap hole to open or close the same.

Each of the electrodes *b*, *b'* and *u* are connected by leads, as shown, with a suitable 80 source of electrical supply. The end of the furnace adjacent to the tapping hole is provided at its center with an orifice, normally closed by a disk *w* of refractory earth and of a thickness equal to the thickness of the 85 end of the furnace.

In the event of accidental fouling of the interior of the furnace, the charge is momentarily interrupted, the heating being continued to exhaust the last fraction of ore 90 which has just been introduced, after which the electric current is interrupted immediately following the emptying of the furnace through the tapping hole. The electrodes are now elevated until their inner ends 95 clear the opening of the furnace, after which the stopper *w* is removed, and by means of a rabble, the furnace may be rapidly cleaned.

The condenser, as shown, consists of a 100 vertical cylinder *l*, furnished with a lining of refractory earth and of a greater diameter at its upper end than at its lower end. A thin walled tube of finely ground, strongly 105 pressed refractory earth or other suitable material offering sufficient resistance of elevated temperatures, and with a minimum porosity, is arranged concentrically with the cylinder *l* and extends from the top to the bottom thereof, a small space being formed 110 between the inner wall of the cylinder and the outer wall of the tube. The tube *2* is

filled with fragments of powder of retort carbon, that is of the same material as the carbons are formed from.

The cylinder is closed at each end by electrodes 3 and 4, which retain the retort carbon in a state of compression. An electric current passes between the electrodes traversing the column of carbon, and heating the said column until the sides of the tube 2 10 become red. The quantity of heat emitted into the condenser by the tube, can be regulated first by varying the intensity of the current passing through the electrodes, second, by the length of the column of carbon, and third by the size and state of comminution of the fragments of carbon in the tube.

The zinc vapors pass through the orifice *t'* into the condenser, and in the opposite 20 side of the condenser from the orifice *t'* is arranged a stopper 5, provided with a swiveling block traversed by a rabble 6, thus permitting the orifice to be cleared when necessary, for example, in case of irregular 25 working of the furnace, without opening any orifice whereby to permit the entry of air. The condensed vapor in the form of liquid zinc, flows from the inclined bottom of the condenser, and is evacuated through 30 the lower orifice 7.

Above the orifice 7 is arranged a stopper 8, the stopper being provided with a swiveling block through which slides a rabble 10.

The essential feature of the condenser, is 35 the heating thereof by a central heating column, under the action of an auxiliary electric current, so arranged as to permit of the regulation of the temperature at will in all parts of the condenser, and the heater 40 may be constructed in any suitable manner which will attain this end.

The electrodes are moved toward and from each other according to the voltage and amperage of the current, whereby to regulate 45 the temperature in the condenser and the cinders and incandescent carbon are caused to pass more or less quickly through the tube to make more or less heat.

In the treatment of calamins, they are introduced into the furnace mixed with the desired weight of reduced fuel and fluxes according to the composition of the gangues.

The blends may be introduced either crude or roasted and when the crude blends are 55 treated they are reduced to the size of coarse sand and mixed with a proportion of filings or of wrought or cast iron waste sufficient to remove all the metal from the sulfid accord-

ing to the reaction. In addition, the flux necessary to increase the fluidity of the slag 60 is also added. The zinc removed by the iron, passes into the condenser as it is set at liberty and reduced to vapor, and the iron sulfid and slag are run off at regular intervals.

It will be evident from the description, 65 that the condenser is electrically heated, the heating being obtained by any kind of electrode, and by the heating of the bed of carbon. It will be observed, that the condenser comprises essentially an outer casing, and an 70 inner casing arranged there within and whose walls are spaced apart from the walls of the outer casing, the inner casing being provided at each end with an electrode which forms the terminals of an electric 75 circuit and that non-fusible material is arranged between the electrodes.

We claim:

1. In a reducing furnace, a condenser comprising an outer casing communicating with 80 the furnace, an inner casing arranged within the outer casing, and spaced apart from the walls thereof, an electrode at each end of the inner casing, the electrodes forming the terminals of an electric circuit, the electrodes 85 being movable toward and from each other, and non-fusible material arranged between the electrodes for the purpose set forth.

2. In a reducing furnace, a condenser comprising inner and outer casings spaced apart 90 from each other, the outer casing communicating with the furnace, electrodes at each end of the inner casing, the electrodes being movable toward and from each other, and a mass of non-fusible material between the 95 electrodes.

3. In a reducing furnace, a condenser comprising a casing communicating therewith, a tube within the casing, an electrode in each end of the tube, and the electrodes being 100 movable toward and from each other.

4. A condenser for furnaces, comprising a casing communicating with the furnace, means within the casing for containing non-fusible material, and a pair of spaced electrodes 105 within the non-fusible material.

The foregoing specification of our electric furnace for the continuous extraction of zinc from its ores signed by us this 6th day of April 1907.
